UNITED STATES PATENT OFFICE

HAROLD L. FIRTION, OF WAREHOUSE POINT, CONNECTICUT, ASSIGNOR TO THE MONTGOMERY COMPANY, OF WINDSOR LOCKS, CONNECTICUT, A CORPORATION OF CONNECTICUT

MOP

Application filed October 25, 1930. Serial No. 491,122.

The present invention relates to mops of the type having a handle, and a head of suitable cleaning material secured to the end of the handle. As an instance of a use to which 5 the present invention may be applied, reference may be had to mops for kitchen use in cleaning dishes, pans, and the like, but it is obvious that my improved mop is not limited to this specific use.

10 The aim of the invention is to provide an improved mop having various features of novelty and advantage, and which is particularly characterized by its simplicity and economy in construction; the ease and facility with which the parts may be manufactured and assembled; and the security with which the mop head is fastened in place on the handle. My improved arrangement is such that danger of splitting the handle is 20 guarded against.

Other objects will be in part obvious, and in part pointed out more in detail herein-after.

The invention accordingly consists in the 25 features of construction, combination of elements and arrangement of parts which will be exemplified in the construction hereinafter set forth and the scope of the application of which will be indicated in the appended 30 claims.

In the accompanying drawing wherein I have shown, for illustrative purposes, one of the many embodiments which the present invention may take,

35 Fig. 1 is a side view of the mop, the head being shown in the form which it has during the attaching operation;

Fig. 2 is a sectional view taken on line 2—2 of Fig. 1;

40 Fig. 3 is a transverse section view taken on line 3—3 of Fig. 2;

Fig. 4 is an exploded view, showing certain of the parts in perspective, and

45 Fig. 5 is an elevational view of a staple and the head-receiving end of the handle, and shows the relation of this staple to the slot in the handle before the staple is inserted in the slot.

50 Referring to the drawing in detail, 10 designates the handle of any suitable shape and

size. The numeral 11 designates the material of which the head is formed; 12, a staple for securing the mop head to the end of the handle; and 13, a ferrule positioned about the forward end of the handle. The handle 55 10 is preferably constructed of wood. The material 11 constituting the mop head may be of any suitable kind, but it is preferably formed of cordage, the strands of which are covered with spirally wound metal ribbons. 60 Cleaning material of this type is disclosed in the patents to J. R. and G. M. Montgomery 1,192,219 and C. B. Elmore 1,212,032. In forming the head, a length of suitable strand material may be wound or folded into a skein, and then the central portion of the skein gathered and secured to the end of the handle by means of the staple, as illustrated. 65 The material 11 is more or less diagrammatically shown in the drawing. 70

In accordance with the present invention, the forward end of the head is provided with a circular or annular slot or groove 15 of a width which is less than the diameter of the wire from which the staple 12 is formed. 75 For example, the width of the slot or groove 15 may be one thirty-second of an inch, and the diameter of the arms 16 of the staple may be three thirty-seconds of an inch. The depth or length of the slot is substantially such that when the staple is driven home, the pointed or tapered ends 17 of the staple touch the bottom of the slot, as shown in Figs. 1 and 2. By preference, the staple is made of resilient metal, and before it is inserted the arms slightly diverge, the over all distance between the arms adjacent their free ends being slightly greater than the outside diameter of the slot. It will be observed from 80 Fig. 5 that the ends of the arms are pointed, and they have outside inclined surfaces or edges 18. 85

In assembling the parts, the ferrule is placed about the reduced forward end of the handle, the skein is formed, and the staple is positioned in straddling relation to the central portion of the skein. Then the points of the staple are brought into registry with the open end of the slot, and the staple is 90 driven home. When the staple is inserted 95 100

into the slot, the arms 16 form grooves in the walls of the slot, and the fiber of the wood surrounding these grooves is placed under compression, with the result that, due to the 5 friction between the arms and the side walls of the slot and the pressure of the wood against those arms, the staple is very securely held in place. Also, when the staple is driven in place, the arms, due to the camming action between the outer periphery of the slot and the inclined surfaces 18, are forced towards each other, thus placing these 10 arms under compression strains which exert force against the outer periphery of the slot, 15 thus giving an added binding and frictional engagement between the arms of the staple and the handle. Owing to the provision of the slot, danger of splitting the handle during assembly of the parts, or after the handle 20 has been put into use, is avoided. It is of advantage to make the slot in the form of an annular concentric groove, as such a slot may be very economically made during the operation of forming or turning the handle, and 25 the insertion of the staple is facilitated, as it is not necessary to bring the handle to any predetermined angular position with respect to the staple-inserting tool or mechanism.

The ferrule reinforces the handle and 30 gives a neat finish to the article. By preference, the forward end of the ferrule extends outwardly beyond the end of the handle in order to form a cup or recess into which the central portion of the mop head is forced 35 when the staple is driven home.

From the foregoing description, taken in connection with the accompanying drawing, it will be seen that my improved mop comprises a relatively small number of parts, 40 each of which may be cheaply made and which parts may be very readily and easily assembled, thus providing a structure which may be economically manufactured and sold at a low cost. The parts are very firmly held 45 together. The likelihood of the head becoming loose is effectively guarded against.

What is claimed is:

1. In a mop, a handle having an annular groove at one end, a head applied to the 50 grooved end of the handle, and a resilient staple having its arms outwardly divergent, the over all distance between the arms adjacent their free ends being greater than the outside diameter of the groove, whereby said 55 arms will bind against the outer wall of said groove when the staple is driven home in the groove, said annular groove facilitating assembly of the handle and staple without particular angular adjustment of the handle 60 relative to the staple.

2. In a mop, a handle having an annular groove at one end, a head applied to the grooved end of the handle, and a resilient staple having its arms outwardly divergent, 65 the over all distance between the arms ad-

jacent their free ends being greater than the outside diameter of the groove, whereby said arms will bind against the outer wall of said groove when the staple is driven home in the groove, said annular groove facilitating assembly of the handle and staple without particular angular adjustment of the handle relative to the staple, said groove also being normally lesser in width than the diameter of said arms whereby said arms partially embed themselves in the walls of the groove when the parts are assembled.
